[57] CLAIM

The ornamental design for a video terminal tilt swivel base, as shown and described.

DESCRIPTION

FIG. 1 is a perspective view of a video terminal tilt swivel base embodying my new design;

FIG. 2 is a front elevational view thereof on an enlarged scale;

FIG. 3 is a top plan view thereof on an enlarged scale;

FIG. 4 is a rear elevational view thereof on an enlarged scale;

FIG. 5 is a left side elevational view thereof on an enlarged scale;

FIG. 6 is a right side elevational view thereof on an enlarged scale; and

FIG. 7 is a bottom plan view thereof on an enlarged scale.
